LEWIS P. WALKER, OF HARTFORD, AND LEO O. BERGMANN, OF COLOMA, MICHIGAN.

FOLDING ROCKING-CHAIR.

Application filed November 30, 1925, Serial No. 72,211.

This invention relates to folding rocking chairs, of the kind in which a folding frame is provided and so constructed that the occupant thereof may, in effect, rock back and forth, but without the necessity of employing actual rockers for the chair.

Generally stated, the object of the invention is to provide a folding rocking-chair of the foregoing general character, having improved means for insuring a satisfactory folding thereof, for storage or transportation, and having means for limiting or controlling the rocking motion, thereby to render the chair safe against collapse or tipping over while in use.

It is also an object to provide certain details and features of construction and combinations tending to increase the general efficiency and the desirability of a folding rocking-chair of this particular character.

To the foregoing and other useful ends, the invention consists in the matters herein-after set forth and claimed, and shown in the accompanying drawing, in which,—

Fig. 1 is a side elevation of a folding rocking-chair embodying the principles of the invention, showing the same in its forward position.

Fig. 2 is a plan of the said chair.

Fig. 3 is a similar view, showing the chair entirely folded up for storage or transportation.

Fig. 4 is a vertical, longitudinal section of the chair, showing the chair in its rearward position.

Fig. 5 is an enlarged detail section on line 5—5 in Fig. 4.

Fig. 6 is an enlarged detail sectional view.

Fig. 7 is a detail sectional view showing another form of the invention.

Fig. 8 is a transverse section on line 8—8 in Fig. 7.

As thus illustrated, the invention comprises, as shown in Figs. 1 to 6, inclusive, the upright inner side members 1, which are rigidly connected by transverse members 2 and 3 near the upper and lower ends thereof. Inclined side members 4 are provided outside of the members 1, and are rigidly connected together by the transverse members 5, 6 and 7, in the manner shown. The members 6 and 7 form the seat, or the front portion thereof. Arm members 8 are pivoted at 9 on the members 1, and arm supporting members 10 are pivoted at 11 on the members 4, as shown, and the members 8 and 10 are connected together,

at each side, by a hinge 12, as shown. In Fig. 1 the arms have reached the articulated limit, obviously, of their unfolding or straightening movement, as the upper end of the member 10 is against the underside of the member 8, forming a stop. The arms thus buckle upwardly to permit the backward rocking motion of the chair. Relatively short side bars 13 are pivoted at 14 on the members 1, and at 15 on the members 4, as shown. An upper back extension is formed by the side members 16, which are pivoted upon the inner sides of the members 1 at 17, and which are connected together by transverse members 18 and 19, thus forming a head rest for the back. This head rest is held in operative position by the pins 20 on the springs 21, which latter are fastened to the outer sides of the members 1, as shown. These pins extend through openings 22 in the members 1, and into the openings 23 in the members 16, thus locking the head rest in position. When the head rest is to be folded downwardly, between the members 1, the springs 21 are pulled outwardly to disengage the pins 20 from the openings 23, in a manner that will be readily understood. A flexible seat and back member 24 is hung on the members 2, 6 and 7, in the manner shown, between the two sides of the chair, thus forming a sort of folding camp-chair. The legs formed by the lower portions of the members 1 and 4 are connected together at each side by toggle members 25 and 26, the two members being pivoted together at 27, and upon the chair legs at 28 and 29, as shown. The members 26, at each side of the chair, are each provided with a shoulder 30 for engaging the shoulder 31 on the adjacent member 25, so that the toggle-joint pivot 27 cannot move below the position shown in the drawings, the two shoulders holding the toggle against any further downward movement. Obviously, the cross piece 5 keeps the supporting means 25 and 26 from buckling upward when the chair is in use.

With the foregoing construction, the occupant of the chair may rock back and forth, with a rocking-chair effect, as indicated in Figs. 1 and 4 of the drawings. The forward movement is limited by the transverse bar 3, previously mentioned, on the portions of the members 1, forming a stop for the lower edges of the members 4, in the manner shown in Fig. 1 of the drawings.

The folding rocking-chair thus constructed

may be folded up in the manner shown in Fig. 3, after first folding the upper head rest downwardly between the members 1, in the manner previously explained, and by then 5 buckling the toggle joints 27 upwardly, in the manner shown, the parts then assuming the various positions shown in Fig. 3 of the drawings, so that the chair may be stored or shipped in convenient and compact condition.

10 As shown in Figs. 7 and 8, the side members 1 have their inner sides provided with ribs 32, and the members 16 have their outer sides provided with grooves 33 to engage these ribs, and there being locking devices, 15 one at each side, like the one shown in Fig. 6 of the drawings and previously described. In this way, when the head rest is unlocked, as shown in Figs. 7 and 8, it can be caused to slide downwardly between the members 1, instead of swinging downwardly in the manner 20 previously explained. Otherwise the construction in Figs. 7 and 8 is similar to that previously described.

As a matter of still further and special improvement, the pivot joints 15 are each preferably of a frictional character, in order to prevent a too jerky motion of the rocking action, and in order to assist in holding the chair in folded condition. As shown in Fig. 30 5, the pivot 15 has the spring tension or frictional means 34 interposed between the members 4 and 13, and these frictional means, of any suitable character, such as spring washers held slightly under tension by the 35 pivot bolt 15, serve to give the chair an easy and slow rocking movement, and serve to assist in holding the chair in folded condition. But, of course, frictional means can be provided in these joints, or in any other 40 joints of the chair, of any suitable character, if so desired.

It will be seen, therefore, that when the chair is in operation there are no movable parts on the floor—that is to say, there are 45 no parts which move back and forth upon the floor. In other words, the lower ends of the portions 25 and 26 rest upon the floor, and the chair can rock back and forth without causing any sliding movement of these parts 50 25 and 26 upon the floor. This is of advantage, of course, as it will prevent the wearing of holes in a carpet or rug, and in addition makes the chair operative without any friction on a bare floor, and renders the chair 55 more satisfactory in use.

Thus the upright members 1 form a stiff back and have front legs rigid therewith, while the members 4 form a seat rigid with the rear legs, all four legs being pivoted at 60 28 and 29 on the articulated or toggle-like supporting means.

It will be seen that the toggle joints 27 are nearer the ends of the rear legs than the front legs, and are a distance in rear of the 65 middle of each stationary support, each sup-

port being formed by the two members 25 and 26, as previously explained. When the chair is folded, these toggle joint supports for the chair fold up as shown in Fig. 3, and are held between the bars or cross pieces 3 and 5, 70 these cross pieces serving to thus limit the upward movement of the toggle joints relatively to the front and rear legs of the chair, when the chair is folded. Thus the toggle joint supports for the chair, and the toggle 75 joint arms for the chair, all fold upwardly, and the elements are so proportioned that the chair will fold compactly and very nearly flat, as shown in Fig. 3 of the drawings.

It will be seen that the toggle members 25 and 26 extend a distance in front of the pivots 28 and a distance in rear of the pivots 29, so that the weight imposed on these pivots tends to keep the toggle joints from rising, and such weight exerts some leverage to keep the pivotal joints 27 in their lowest position. 85

Without disclaiming anything, and without prejudice to any novelty disclosed, what we claim as our invention is:

1. In a folding rocking chair, the combination of means forming a seat and back and front and rear legs, and means forming two stationary supports on the floor, upon which the front and rear legs are pivoted, each support comprising two laterally overlapping sections forming a toggle joint between them, said joint having a pivot extending through the overlap, these supports each having its front end pivoted to a front leg and its rear end pivoted to a rear leg, with a stop between each front support and the front end of the rear support, serving to limit the downward movement of the toggle joints and hold them in raised position a distance above the floor, the chair back being rigid with the front legs, and the rear legs being rigid with the front edge portion of the seat. 90

2. A structure as specified in claim 1, and a cross piece connecting the two rear legs together, serving as a stop to limit the upward movement of the toggle joints relatively to the rear legs, and a cross piece on the front legs serving as a stop to limit the upward folding movement of the toggle joints relatively to the front legs, when the chair is 100 folded. 110

3. A structure as specified in claim 1, said toggle joints being nearer the rear ends of said supports than the front ends thereof, and folding arm connections between the back and the sides of the seat portion of the chair, each arm connection having a toggle joint therein, permitting rocking motion of the chair, and all of said toggle joints being foldable upwardly when the chair is folded. 120

4. In a folding rocking chair, the combination of pivotally connected elements forming a folding frame comprising a stiff back and front legs rigid therewith, and capable of back and forth rocking motion when in 130

use, articulated supporting means formed by two laterally overlapping front and rear members pivoted together through the overlap at each side of the chair, upon which the 5 legs of the chair are pivoted, adapted to remain stationary on the floor during such forward and back rocking motion, forming toggle joints adapted to fold and break joint upwardly when the frame is folded, a seat 10 portion rigid with the rear legs, extending forward of the lower ends of the front legs, and a flexible seat and back member hung on said seat portion and back of the frame, said articulated supporting means being extended 15 forward a distance to bear on the floor at points a distance in front of the lower ends of the front legs, serving to keep the toggle joints from rising during rocking motion of the chair, said seat and back member being 20 flexible to permit folding of said frame and said articulated supporting means in the desired manner, with said front extensions of the articulated supporting means forming one extreme end of the flattened structure 25 formed by the folding chair.

5. In a folding chair adapted to rock back

and forth freely, with a motion similar to an ordinary rocking chair, the combination of frame members forming front legs rigid with a stiff back, frame members forming a seat 30 rigid with rear legs, means movably connecting the first mentioned members with the second mentioned members, combining therewith to form a folding and rocking frame, rear toggle member supports upon which the 35 rear legs are pivoted, front toggle members upon which the front legs are pivoted, the rear toggle members having laterally overlapping pivotal toggle joint connections with the front toggle members, stops on said members to limit the downward movement of the 40 toggle joints, serving to keep the toggle joints raised a distance from the floor, and front extensions for said front toggle members, said extensions bearing upon the floor 45 to prevent said toggle joints from rising during the rocking motion of the chair.

Specification signed this 31st day of October, 1925.
